UNITED STATES PATENT OFFICE

150,539

DESIGN FOR A LITURGICAL FABRIC OR SIMILAR ARTICLE

Apollinaris Baumgartner, New York, N. Y.

Application May 17, 1947, Serial No. 139,101

Term of patent 7 years

(Cl. D92—1)

To all whom it may concern:

Be it known that I, Apollinaris Baumgartner, a citizen of the United States of America, resident of New York city, county, and State of New York, have invented a new, original, and ornamental Design for a Liturgical Fabric or Similar Article, of which the following is a specification, reference being had to accompanying drawing, forming part thereof.

In the drawing: the figure is a plan view of the liturgical fabric embodying the design.

I claim:

The ornamental design for a liturgical fabric or similar article, substantially as shown.

APOLLINARIS BAUMGARTNER.
